SLICING MACHINE

William J. Campbell, Indianapolis, Ind., assignor
to American Slicing Machine Company, Chi-
cago, Ill., a corporation of New York

Application August 9, 1934, Serial No. 739,104

17 Claims. (Cl. 146—102)

My invention relates to an improvement in slicing machines and has for one purpose the provision of an improved pusher plate actuating mechanism for the carriage of a so-called manual feed slicing machine. Another purpose is the provision of improved means for yieldingly urging the pusher plate, in such type of machine, toward the cutting plane. Another object is the provision of ready means for connecting and disconnecting said yielding means. Another object is the provision of means for varying the force of said yielding means. Another object is the provision of means for throwing the pusher plate away from the cutting plane when it is rotated upwardly from the carriage at a point adjacent the cutting plane. Another purpose is the provision of improved means for holding the pusher plate locked in inoperative position to permit the ready manual feed of material toward the cutting plane. Another object is the provision of improved guiding or securing means for holding and guiding work upon the carriage. Another object is the provision of improved means for preventing the pusher plate from moving forwardly into the cutting plane when moved adjacent the cutting plane. Another object is the provision of improved work engaging members for the forward portion of the cutting plane. Another object is the provision of improved sharpening means for the knife of a slicing machine. Another object is the provision of improved work supporting means for supporting the work at the instant at which the slice is severed from the work.

Other objects will appear from time to time in the course of the specification and claims.

I illustrate my invention more or less diagrammatically in the accompanying drawings, where-
in—

Figure 1 is a front elevation;

Figure 2 is a plan view with parts in horizontal section;

Figure 3 is an end elevation;

Figure 4 is a perspective showing the parts in a somewhat different position;

Figure 5 is a section on the line 5—5 of Figure 1;

Figure 6 is a section on the line 6—6 of Figure 1;

Figure 7 is a section on the line 7—7 of Figure 4;

Figure 8 is a vertical section through a portion of the sharpening means;

Figure 9 is a partial plan view of the structure shown in Figure 8;

Figure 10 is a section on the line 10—10 of Figure 1;

Figure 11 is a section on the line 11—11 of Figure 10;

Figure 12 is a partial plan view and variant 5 illustrating primarily the carriage structure;

Figure 13 illustrates a modified form of the structure shown in Figure 12;

Figure 14 is a variant form of spring support 10 for the pusher plate; and

Figure 15 shows a variation of the structure shown in Figure 14.

Like parts are indicated by like symbols 15 throughout the specification and drawings.

Referring to the drawings, A is a base having anti-frictional studs or rubber pads or the like A¹ for contacting the counter or support.

B indicates any suitable motor which is provided with a drive pulley B¹ about which passes 20 a belt B² which in turn passes about a driven pulley B³ mounted on a knife shaft B⁴ and serving to rotate it. The knife B⁵ is mounted on the same shaft and is therefore rotated in response to rotation of the motor pulley B¹. 25

A frame portion generally indicated at C extends up from the base and is shown as having integral therewith a sleeve portion C¹ in which the knife shaft B⁴ is rotatably mounted in any suitable manner. C² is a cover for the housing 30 thus formed and C³ is a removable guard plate closing the front of the housing and masking the major part of the face of the knife B⁵. The knife B⁵ is shown as forwardly hollowed as at B⁶ and into this hollow penetrates the arcuate 35 edge C⁴ of the guard plate C³. The guard plate is offset at its upper edges at C⁵ and is provided with a scraper C⁶ secured to the lower portion thereof and opposed to the knife. It may be held in position for example by lower securing means 40 C⁷ and upper securing screws C⁸, C⁹ which control spring clips C¹⁰ whereby the upper edge of the guard plate is locked in position. The details of the securing means do not of themselves 45 form part of the present invention and therefore are not exhaustively indicated.

Forward tracks D, D¹ are positioned in front of the cutting plane of the knife. Mounted thereon is a carriage structure generally indicated as 50 D² and including a bearing D³ surrounding one of the tracks D and a roller D⁴ engaging the outermost of said tracks. Said roller is held in operating relationship with the track as, for example, by the adjustable pin or stud D⁵ mount- 55

ed on the bracket structure D^6 in which the roller D^4 is rotatably mounted.

Mounted upon the carriage is a work supporting surface member E which is provided with a plurality of upward ridges E^1 generally perpendicular to the cutting plane but which are broken by a level portion E^2 which forms a gap through the ridges E^1 extending from end to end of the member E in general parallelism with the cutting plane. At one end the member E is upwardly bent as at E^3 to form a flange perpendicular to the cutting plane and also generally perpendicular to the member E as a whole. It has a rolled top E^4 which is susceptible of use as a manual handle in actuating the carriage itself or in urging the work on the carriage toward the cutting plane. E^5 is an additional manual handle located on a flange E^6 which extends upwardly from the carriage and abuts against the member E^3 . It also has an upward extension E^7 as shown in Figures 1 and 4 which may extend to the full height of the below described gauge plate. E^8 is a knife guard member secured to the member E^7 and perpendicular to it and so formed and positioned as to mask the cutting edge of the knife when the carriage is at the end of its cutting stroke. E^9 is a second flange at the opposite end of the member E and also perpendicular to the member E and to the cutting plane. It is mounted upon a bracket E^{10} which bracket is bolted or otherwise secured to the carriage as by the screws E^{11} . Also bolted to the bracket E^{10} is a bar E^{12} upon which is mounted a rod E^{13} the opposite end of which is secured to the member E^6 . The rod E^{13} is held in position as by a lock nut E^{14} and is screwthreaded as at E^{15} into the member E^{12} . It is provided with a reduced portion E^{16} the purpose of which will later appear.

Longitudinally movable along the rod E^{13} is a sleeve G which is also rotatable about the rod E^{13} . It has an offset portion G^1 to which is secured an abutment member G^2 which when in the operative position as that in which it is shown in Figure 4 terminates closely adjacent the cutting plane of the knife. It has a lug G^3 aligned with the flat portion E^2 of the work support E . The plate G^2 may be rotated about the rod E^{13} but when in use it is in the position in which it is shown in Figure 4 and may be moved longitudinally along the rod E^{13} , through a range which is almost as great as the distance between the flanges E^3 and E^9 . When it is opposed to the flange E^9 it is then locked against unintended movement as by the plug G^4 which is urged by the spring G^5 controlled by the abutment screw G^6 which also serves as a handle for moving the device. Preferably the loading of the spring G^5 is such that the plug G^4 with its tapered end G^7 will rest in the slot E^{16} in the rod E^{13} and hold the member G^2 firmly against the face of the flange E^9 until the operator again wishes to use it. The loading of the spring is not enough, however, to prevent an intended manual movement of the device. The sleeve G is sufficiently short so that when the member G^2 is moved against a piece of meat or any flexible material the pressure of the material is enough to bind the sleeve G on the rod E^{13} and thus more or less lock or hold the work in position against either the flange E^3 or the flange E^9 , depending upon which flange is being employed as an abutment for the work.

In this type of machine I prefer to use a gauge plate as shown, for example, at H , although the 75 details of the gauge plate do not of themselves

form part of the present invention. Any suitable means may be employed for moving and guiding the gauge plate H toward and away from the cutting plane of the knife. I illustrate, for example, a supporting bracket H^1 actuated by a handle H^2 . To the rear of the cutting plane is any suitable slice receiving member herein indicated as H^3 . The inner edge of the gauge plate H is notched as at H^4 to receive a slice or work support H^5 which has a bevelled surface positioned generally at the level of the work support E . The work support H^5 is mounted upon a supporting member H^6 which has an arcuate edge H^7 opposed to the cutting edge of the knife with a clearance increasing in the direction of rotation of the knife which is indicated by the arrow in Figure 1. Similarly the arcuate edge H^8 of the gauge plate has an increasing clearance in the direction of rotation of the knife. This clearance is quite slight and hardly shows up in a drawing of the scale of those herein shown, but it will be understood that this increase in clearance in the direction of rotation of the knife does exist. I may find it advantageous to have the slice support H^5 formed integrally with the knife edge guard portion H^6 , the piece being removable as a unit from the slicing machine. Or I may make the slice support adjustable in relation to the knife edge guard portion H^6 .

We will next consider the pusher plate structure. In a slicing machine of the type in which a manually actuated carriage is employed in connection with a gauge plate, the thickness of the slice is determined by the setting of the gauge plate. The work may be thrust manually across the slice support E without the employment of any pusher plate structure whatsoever. The device, when so used, is as shown in Figure 4. In such case the guide member G^2 may either be in inoperative position against the flange E^9 or it may be used to grip work against either the flange E^9 or the flange E^3 , at the convenience of the operator. When the device is to be employed in connection with a pusher plate the guide G^2 may be moved into inoperative position adjacent the flange E^9 . The pusher plate structure, below described, can then be placed in operative position above the work support E . The guide G^2 may be made no higher than the thickness of a moderately thin piece of bacon so that, if the guide G^2 is used, the bottom rows of extending prongs L^2 , L^4 will contact the material which is crowded between the guide G^2 and either flange E^3 or E^9 . The pusher plate structure is as follows. I employ a guide pin J having a knob at the end J^1 separated by a tapered neck J^2 from the body of the rod. The head or knob has a sloped or reduced forward end J^3 . The pin or rod J may be secured in position upon the carriage structure as at J^4 which is an extension from the member E^{10} . It may be apertured as at J^5 to receive a reduced portion J^6 of the pin and this portion is held in place as by the locking nut J^7 . J^8 is an inclined fixed cam structure, shown, for example, in Figure 2, the purpose for which will later appear.

Slidable and rotatable upon the pin J is a sleeve K which has a plurality of terminal radial fins K^1 . It also has an offset to support a roller K^2 opposed to the cam track J^8 . The sleeve K is provided also with a major offset extension K^3 with a manual handle K^4 on the portion thereof. This extension K^3 terminates in a sleeve K^5 which has another handle K^6 associated therewith. The sleeve K^5 is apertured to receive a rotating sleeve 75

K⁷ through which passes the screw K⁸ to which is connected the handle K⁶. The screw K⁸ is connected to a pusher plate structure which will be described in detail below. K¹⁰ is a nut on the screw K⁸ which serves as an abutment opposed to the frictional member K¹¹ which is thrust by the coil spring K¹² against the nut K¹⁰. The coil spring K¹² has also for effect to cause a friction between the handle K⁶ and the sleeve 10 K⁵ whereby rotation of the pusher plate structure in relation to the sleeve K⁵ is made sufficiently difficult to prevent an unintended relative rotation, while permitting ready intended manual rotation.

15 The pusher plate structure includes the main pusher plate member L which is held against rotation in relation to the screw K⁸. It has forwardly extending points L¹ and at the bottom downwardly and forwardly extending prongs L² which preferably are so proportioned and disposed that their points are all in the same general plane as the points of the members L¹. I also employ a rearwardly extending flange L³ having points or prongs L⁴ at the rear edge thereof as shown, for example, in Figure 10. They are also slanted forward as shown in that figure.

In order to limit the arc of relative rotation of the pusher plate L, I provide a stop L⁵ which is adjustable and is eccentrically mounted as upon the screw L⁶ as shown for example in Figure 10. The stop L⁵ engages an abutment L⁷ which may for example be a fiber roller and which is mounted as by the screw L⁸ upon an offset K²⁰ from the bracket K³. Rotary adjustment of the stop L⁵ varies the limit of rotation of the plate L in relation to the bracket K³ upon which it is mounted. To support the outer end of the pusher plate L, I provide a bracket or arm L¹⁰ which may have any suitable contact member L¹¹ which may be of fiber and which rides upon the rolled top E⁴ of the flange E³. Also, the bracket L¹⁰ is so proportioned as to serve as a stop, in connection with the member E⁷, to limit the movement of the outer end of the pusher plate toward the cutting plane and to prevent any of the points or prongs of the pusher plate from getting into the cutting plane.

The sleeve K is freely rotatable about the rod J throughout the entire excursion of the sleeve K along said rod. However, as earlier mentioned, the cam J⁸ serves as a throwout to withdraw the pusher plate rearwardly away from the cutting plane in response to a rotation of the pusher plate structure when it is within a predetermined distance of the cutting plane. When it is so withdrawn or rotated at that point, at the termination of the camming retraction the knob K⁴ is properly positioned to be engaged by a latch M which is yieldably thrust as by the spring M¹, 40 into locking position. It has a slightly inclined locking surface M² opposed to the knob K⁴ and an inclined surface M³ over which the knob can ride until it reaches the locking position and the spring M¹ thrusts the latch M into the position in which it is shown in Figure 7. The latch M is slidably mounted in a sleeve M⁴ which is mounted upon or forms part of the member E¹⁰. Thus by a single easy movement of the hand the operator can rotate the pusher plate into inoperative position and it is held by the latch M in the position shown, for example, in Figure 4. In order to prevent the latch M from rotating I provide a screw M⁵ which engages a groove M⁶ extending along one side of the member M. It will be noted that the inner bevel of the knob K⁴

conforms to the bevel M² of the member M. M⁷ is a stem extending from the member M which terminates in an exterior portion M⁸ to which is secured a handle portion M⁹ as shown, for example, in Figure 3. M¹⁰ is any suitable securing nut. It will be clear that the hook shaped handle M⁹ is easily available for a manual release of the latch M, whereby the pusher plate can then be rotated back into operative position. I also provide an abutment member M¹¹ which limits the movement of the pusher plate structure toward the sleeve M⁴. It is illustrated in Figure 7 and is shown as adjustable and may be locked in any desired position as by the nut M¹².

In order to provide means for yieldingly moving the pusher plate structure towards the cutting plane I illustrate a manually controlled handle generally indicated as O and having a hook O¹ and a prong O² adapted to penetrate, at selection, any one of the circumferential notches K¹ 15 of the sleeve K. The member O is secured as by a coil spring O³ which in turn is anchored as at O⁴ to the carriage structure. The power of the spring is such that the operator can readily draw it out to engage it at will in any one of the circumferential notches K¹. The tension of the spring is thereby subject to a certain adjustment or control, as the force directed by the spring is increased in ratio to the distance of the particular notch K¹ from the inner end of the sleeve 20 K. When it is desired to release the prong O² the operator may grasp the handle O¹ and withdraw the prong O² from the circumferential notch K¹ and engage it on the side of the flange E⁹ as at E²⁰. There is sufficient flexibility in the 25 spring for this to be done readily and practically instantaneously by a simple movement of the hand. It is desirable to provide a reasonable flexibility of the spring but it is also desirable somewhat to limit its flexure or to give it some 30 intermediate guide or reinforcement. This may be done in a number of ways. I illustrate in Figure 6, for example, a tube O⁵ which may be fairly rigid and which extends through a substantial part of the spring O³. It may be penetrated as 35 by the pin O⁶ which slides in relation to it and which penetrates its central aperture. Preferably there should be sufficient clearance so that enough lateral flexure is allowed to permit the prong O² readily to be moved into and out of 40 locking position and into and out of inoperative securing position at the point E²⁰.

A variant form of obtaining the same result is shown in Figure 14 in which a pin O²⁵ is employed with a tapered end, the pin being fixed in 45 relation to the carriage. This pin may be made solid and rigid as in Figure 14 or it may have substituted for it, as in Figure 15, a flexible rod O²⁶ with a tapered and enlarged head O²⁷. In any case, it will be understood that some means 50 may be employed for more or less guiding and reinforcing the spring O³ while permitting sufficient flexure to allow it readily to act. In the form of Figure 14 the pin O²⁵ is sufficiently tapered to prevent its passing through the coils 55 of the spring, the spring being preferably rather tightly coiled. In the form of Figure 15 the pin O²⁶ flexes somewhat with the spring.

An important feature of my device rests in the ready removability of the sleeve K from the 60 pin J. This is illustrated, for example, in Figure 3, taken in connection, say, with Figure 6. The terminal knob J¹ with its inclined or tapered outer end J³ can be ever readily engaged with the end of the sleeve K. When the sleeve 65

K is thus urged along the rod it engages the inclined surface J², up which it rides. The result is a self-alignment of the sleeve K upon the rod J which makes its application to the rod a 5 very easy and simple matter. This is a rather important point as it is in practice rather difficult to align such a sleeve with a rod and avoid binding and difficulty in application which is delaying and vexatious, especially when the operator is in a hurry to get an order sliced and, 10 after having used the device with the pusher plate structure entirely removed, is trying to put it back on the machine preparatory to cutting some material. Also, the length of the sleeve K 15 tends to prevent binding, once it is aligned with the rod J.

I illustrate in Figures 8 and 9 an improved sharpening device for the knife. It includes in the main a sharpening structure or lever P pivoted as at P¹, upon any suitable screw or bolt. The pivot point is generally in or closely adjacent the cutting plane of the knife or rather the plane of the body of the knife, although a slight variation is immaterial. The lever P has a continuing handle P⁸ which extends through the cover C² through any suitable aperture. I employ a spring rod P², one end of which is secured as at P³ to the lever P. Its other end is secured as at P⁴ to an adjustable support P⁵ which 20 may be held in any adjusted position as by the screw P⁶ passing through the slot P⁷, whereby the location of the spring P² may be varied in relation to the upstanding frame portion of the slicing machine. Mounted upon the lever P are 25 a plurality of sharpening elements indicated as P⁹ and P¹⁰ respectively, one being opposed to each side of the edge of the knife. The spring P² is preferably so set as to keep both sharpening devices in neutral position. The operator, by 30 thrusting the handle P⁸ in one direction, engages one of the sharpening members with one side of the cutting edge. When he thrusts the handle in the opposite direction he engages the other sharpening member with the opposite edge of 35 the knife. The force with which the sharpening members are applied is entirely manually controlled. Only one can be engaged at once, and unless the operator is actually applying force to the handle P⁸ neither sharpening device 40 is engaged. The sharpening member can also be vertically adjusted on the screw P¹. It is provided, for example, with a sleeve P¹² surrounding the screw, its downward movement being 45 limited by any suitable abutment or washer P¹³ against which it is normally thrust as by the spring P¹⁴. The screw P¹ is itself screwthreaded into an upper portion of the frame as at P¹⁵, and as it is rotated as by the screw driver slot P¹⁶ it moves up and down and thus raises or lowers 50 the sleeve P¹². P¹⁷ is any suitable lock nut. Thus, as the knife wears down, the location of the sharpening mechanism may be lowered to compensate for the wear or, when a new and larger 55 blade is applied, it may be raised to compensate for the increased diameter of the new knife blade.

I illustrate in Figures 12 and 13, a slight variation in the employment of the intermediate support or guides between the flanges of the work support. I illustrate, for example, the rod S mounted at one end on the straight bracket S¹ and at the opposite on the crooked or extension bracket S². This extension gives room for the sleeve G to move sufficiently far to the left, referring to the position of the parts in Figure 12, to 60 permit the blade G² to abut against the left hand

work engaging flange E³. Where but a single member G² is employed this permits it to move through an excursion substantially equivalent to the distance between the opposed flanges. Where two of the members G² are employed, as is shown in Figures 12 and 13, then one of the guides G² 5 may be moved into opposition to one of the flanges E³ and the other be moved at the same time into closed opposition to the other flange E⁹, or both of them may be moved into opposition with the flange E⁹ as shown in Figure 13. In Figure 13 10 a further variation is shown, in order to make this possible, namely the mounting of one of the members G² on an offset bracket S³ on one of the sleeves G which rides on the rod S. 15

Where two of the guides G² are employed, as shown in Figure 13, two pieces of material can be sliced in the machine at the same time, one being crowded against the flange E³ by one of the guides G² and the other being crowded against 20 the flange E⁹ by the other guide G². The user can slice two pieces at the same time by the use of the pusher plate, or he can slice one piece at a time by the use of the pusher plate. If he wishes to slice a piece of meat lying against the 25 flange E⁹ only, when two pieces are on the carriage, he can move back from the cutting plane the piece which is lying against the flange E³. Of course, both pieces would be simultaneously moved toward the cutting plane by the action of 30 the thrusting member, but one of them will be in the position to be sliced and the other would be so remote from the cutting plane as not to be sliced. This possibility of selectively slicing either 35 one of two pieces, without removing either one of them from the carriage is radically new and highly advantageous. By being able to slice material on either side of the carriage the machine is convenient for a long armed as well as a short 40 armed user. Where it is inconvenient to crowd the material against the flange E³, because of the location of the carriage, as on a shelf adjacent a wall, the material can be placed in contact with the flange E⁹ and held there by one of the 45 guides or crowders G².

The bracket or arm L¹⁰ may also be used as a handle for operating the pusher plate. This is a convenient method of operating the pusher plate because the user can put his thumb under the flange E⁴ and his hand over the flange E⁴ 50 to reciprocate the carriage, using the index finger to feed the pusher plate with pressure against the member L¹⁰.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic, rather than as limiting me to my specific showing.

I claim:

1. In a slicing machine having a knife and means for actuating it, and a gauge plate movable toward and away from the cutting plane of the knife, a carriage and means for guiding it across the face of the gauge plate and past the cutting edge of the knife, guiding ridges on said carriage, generally perpendicular to the cutting 65 plane of the knife, said ridges having aligned interruptions extending in parallelism with the cutting plane, an intermediate flange movably positioned upon said carriage and movable along a path parallel with the cutting plane and an en- 70 75 80 85 90 95 98

gaging member, associated therewith, and aligned with said interruptions and adapted to maintain a supporting contact with the carriage as it moves therealong and through said interruptions.

2. In a slicing machine having a knife and means for actuating it, and a gauge plate movable toward and away from the cutting plane of the knife, a carriage and means for guiding it across the face of the gauge plate and past the cutting edge of the knife, a pusher plate mounted upon the carriage and means for guiding it for movement toward and away from the cutting plane, including a generally horizontal guide mounted upon the carriage generally perpendicular to the cutting plane, a supporting connection intermediate guide and pusher plate including a member longitudinally and rotatably mounted upon the guide and means, responsive to upward rotation of said supporting connection and pusher plate about the guide and away from the carriage, for retracting the pusher plate from the cutting plane of the knife, when the pusher plate, at the beginning of its rotation, is within a predetermined distance of the cutting plane.

3. In a slicing machine having a knife and means for actuating it, and a gauge plate movable toward and away from the cutting plane of the knife, a carriage and means for guiding it across the face of the gauge plate and past the cutting edge of the knife, a pusher plate mounted upon the carriage and means for guiding it for movement toward and away from the cutting plane, including a generally horizontal guide mounted upon the carriage generally perpendicular to the cutting plane, a supporting connection intermediate guide and pusher plate including a member longitudinally and rotatably mounted upon the guide and means, responsive to upward rotation of said supporting connection and pusher plate about the guide and away from the carriage, for retracting the pusher plate from the cutting plane of the knife, when the pusher plate, at the beginning of its rotation, is within a predetermined distance of the cutting plane, and latching means adapted to latch said pusher plate in raised position at the termination of a predetermined camming rotation.

4. In a slicing machine having a knife and means for actuating it, and a gauge plate movable toward and away from the cutting plane of the knife, a carriage and means for guiding it across the face of the gauge plate and past the cutting edge of the knife, a pusher plate mounted upon the carriage and means for guiding it for movement toward and away from the cutting plane, including a generally horizontal guide mounted upon the carriage generally perpendicular to the cutting plane, a supporting connection intermediate guide and pusher plate including a member longitudinally and rotatably mounted upon the guide and means, responsive to upward rotation of said supporting connection and pusher plate about the guide and away from the carriage, for retracting the pusher plate from the cutting plane of the knife, when the pusher plate, at the beginning of its rotation, is within a predetermined distance of the cutting plane, and latching means adapted to latch said pusher plate in raised position at the termination of a predetermined camming rotation, including a member associated with the pusher plate and a plunger mounted upon the carriage, said plunger including an inclined surface adapted to be overridden by the member on the pusher plate and a

locking surface adapted lockingly to engage said member after the member has overridden the first mentioned inclined surface, and yielding means adapted normally to hold said plunger in latching position.

5. In a slicing machine having a knife and means for actuating it, and a gauge plate movable toward and away from the cutting plane of the knife, a carriage and means for guiding it across the face of the gauge plate and past the cutting edge of the knife, a work support on said carriage having opposed and normally fixed flanges at opposite edges thereof, transverse to the cutting plane of the knife, said flanges being of sufficient height to grip pieces of meat of substantial size, an intermediate flange movably positioned between said normally fixed flanges, and guiding means therefor adapted to maintain it, during its movement, in parallelism with said fixed flanges, said intermediate flange being of the same order of height as the fixed flanges, the opposed face portion of the intermediate and fixed flanges being adapted to grip therebetween the work supported on the carriage, said intermediate flange being operable against either of the normally fixed flanges, the guiding means for said movable flange being removed from the normal path of movement of the work, and securing means operable in response to clamping pressure between said movable flange and either of said fixed flanges to secure said intermediate flange against movement.

6. In a slicing machine having a knife and means for actuating it, and a gauge plate movable toward and away from the cutting plane of the knife, a carriage and means for guiding it across the face of the gauge plate and past the cutting edge of the knife, a work support on said carriage having opposed and normally fixed flanges at opposite edges thereof, transverse to the cutting plane of the knife, said flanges being of sufficient height to grip pieces of meat of substantial size, an intermediate flange movably positioned between said normally fixed flanges, and guiding means therefor adapted to maintain it, during its movement, in parallelism with said fixed flanges, said intermediate flange being of the same order of height as the fixed flanges, the opposed face portion of the intermediate and fixed flanges being adapted to grip therebetween the work supported on the carriage, said intermediate flange being operable against either of the normally fixed flanges, the guiding means for said movable flange being removed from the normal path of movement of the work, and securing means operable in response to clamping pressure between said movable flange and either of said fixed flanges to secure said intermediate flange against movement, said guiding means being adapted to permit said intermediate movable flange to move through a range substantially equal to the distance separating the two normally fixed flanges.

7. In a slicing machine having a knife and means for actuating it, and a gauge plate movable toward and away from the cutting plane of the knife, a carriage and means for guiding it across the face of the gauge plate and past the cutting edge of the knife, a work support on said carriage having opposed and normally fixed flanges at opposite edges thereof, transverse to the cutting plane of the knife, and a plurality of movably mounted flanges positioned between said normally fixed flanges, said fixed and mov-

ing flanges extending upwardly from the surface of the work support in general perpendicularity to said support, and to generally the same height, the opposed faces of the fixed and movable flanges being adapted to grip the work positioned on the work support, one of said moving flanges being operable against one of the fixed flanges, and the other being operable against the other, the two movable flanges being adapted also to compress the material therebetween, and guiding means for said movable flanges, and securing means for said movable flanges, said guiding and securing means being positioned at a point removed from the feed trough space defined between the fixed flanges.

8. In a slicing machine having a knife and means for actuating it, and a gauge plate movable toward and away from the cutting plane of the knife, a carriage and means for guiding it across the face of the gauge plate and past the cutting edge of the knife, a work support on said carriage and a pusher plate mounted for movement above said work support toward and away from the cutting plane of the knife, a guide, along which said pusher plate is slidably movable, and means for yieldingly urging the pusher plate toward the knife, including a coil spring secured to the carriage at one end, adjacent the cutting plane, and extending in general parallelism with said slideable guiding means, a handle and catch mounted on the other end, and supported by said spring, and means, associated with said pusher plate, for receiving said catch, said spring being freely flexible laterally toward and away from said guiding means and pusher plate.

9. In a slicing machine having a knife and means for actuating it, and a gauge plate movable toward and away from the cutting plane of the knife, a carriage and means for guiding it across the face of the gauge plate and past the cutting edge of the knife, a work support on said carriage and a pusher plate mounted for movement above said work support toward and away from the cutting plane of the knife, a guide, along which said pusher plate is slidably movable, and means for yieldingly urging the pusher plate toward the knife, including a coil spring secured to the carriage at one end, adjacent the cutting plane, and extending in general parallelism with said slideable guiding means, a handle and catch mounted on the other end, and supported by said spring, and means, associated with said pusher plate, for receiving said catch, said spring being freely flexible laterally toward and away from said guiding means and pusher plate, and a rigid guide for said spring, shorter than the spring, adapted to limit the flexure of a portion of said spring, while permitting ready and substantial lateral flexure of the outer end of the spring and catch.

10. In a slicing machine having a knife and means for actuating it, and a gauge plate movable toward and away from the cutting plane of the knife, a carriage and means for guiding it across the face of the gauge plate and past the cutting edge of the knife, a work support on said carriage and a pusher plate mounted for movement above said work support toward and away from the cutting plane of the knife, a guide, along which said pusher plate is slidably movable, and means for yieldingly urging the pusher plate toward the knife, including a coil spring secured to the carriage at one end, adjacent the cutting plane, and extending in general parallelism with said slideable guiding means, a handle and catch

mounted on the other end, and supported by said spring, and means, associated with said pusher plate, for receiving said catch, said spring being freely flexible laterally toward and away from said guiding means and pusher plate, and a flexible guide for said spring, adapted to permit lateral flexure of the spring sufficient to allow the engagement of the catch with the pusher plate. 5

11. In a slicing machine having a knife and means for actuating it, and a gauge plate movable toward and away from the cutting plane of the knife, a carriage and means for guiding it across the face of the gauge plate and past the cutting edge of the knife, a work support on said carriage and a pusher plate mounted for movement above said work support toward and away from the cutting plane of the knife, a guide, along which said pusher plate is slidably movable, and means for yieldingly urging the pusher plate toward the knife, including a coil spring 10 secured to the carriage and extending in general parallelism with said slideable guiding means, a handle and catch mounted on and supported by said spring, and means, associated with said pusher plate, for receiving said catch, said spring being freely flexible laterally toward and away from said guiding means and pusher plate, said pusher plate being provided with a plurality of members adapted to receive said catch, said receiving members being located along said guide at varying distances from the cutting plane of the knife, said members constituting a plurality of concentric longitudinally spaced cups positioned along said guide. 15 20 25

12. In a slicing machine having a knife and means for actuating it, and a gauge plate movable toward and away from the cutting plane of the knife, a carriage and means for guiding it across the face of the gauge plate and past the cutting edge of the knife, a work support on said carriage and a pusher plate mounted for movement above said work support toward and away from the cutting plane of the knife, a guide, along which said pusher plate is slidably movable, and means for yieldingly urging the pusher plate toward the knife, including a coil spring secured to the carriage and extending in general parallelism with said slideable guiding means, a handle and catch mounted on and supported by said spring, and means, on said pusher plate, for receiving said catch, said spring being freely flexible toward and away from said guiding means and pusher plate, the catch receiving means on the pusher plate including an annular flange surrounding the axis of said guide. 30 35 40 45 50 55

13. A pusher plate for slicing machines, which includes a plate, means for holding and guiding it in generally vertical position, a row of downwardly and forwardly inclined points at the lower edge of said plate and a unitary flange secured to the lower edge of said plate at one edge and having a plurality of downwardly and forwardly inclined points extending from its opposite edge, the points of said flange and of the lower edge of the pusher plate all terminating in substantially a single and generally horizontal plane, and a plurality of points extending forwardly from the forward face of the pusher plate, the first mentioned points along the lower edge of the pusher plate lying in a generally vertical plane common to the ends of said last mentioned points. 60 65 70

14. In a slicing machine having a knife and means for actuating it, and a gauge plate movable toward and away from the cutting plane of 75

the knife, a carriage and means for guiding it across the face of the gauge plate and past the cutting edge of the knife, a work support on said carriage and a pusher plate mounted for movement above said work support toward and away from the cutting plane of the knife, a guide, along which said pusher plate is slidably movable, and means for yieldingly urging the pusher plate toward the knife, including a spring secured to the carriage at one end, adjacent the cutting plane, and extending in general parallelism with said slidable guiding means, a handle and catch mounted on the other end, and supported by said spring, and means, associated with said pusher plate, for receiving said catch, said spring being freely flexible laterally toward and away from said guiding means and pusher plate.

15. In a slicing machine having a knife and means for actuating it, a carriage and means for guiding it past the cutting edge of the knife, a pusher plate mounted upon the carriage and means for guiding it for movement toward and away from the cutting plane, including a generally horizontal guide mounted upon the carriage, generally perpendicular to the cutting plane, a supporting connection intermediate guide and pusher plate including a member longitudinally and rotatably mounted upon the guide and means, responsive to rotation of said supporting connection and pusher plate about the guide and away from the carriage, for retracting the pusher plate from the cutting plane of the knife, when the pusher plate, at the beginning of its rotation, is within a predetermined distance of the cutting plane.

16. In a slicing machine having a knife and means for actuating it, a carriage and means for guiding it past the cutting edge of the knife, a pusher plate mounted upon the carriage and means for guiding it for movement toward and away from the cutting plane, including a generally horizontal guide mounted upon the carriage, generally perpendicular to the cutting plane, a supporting connection intermediate guide and

pusher plate including a member longitudinally and rotatably mounted upon the guide and means, responsive to rotation of said supporting connection and pusher plate about the guide and away from the carriage, for retracting the pusher plate from the cutting plane of the knife, when the pusher plate, at the beginning of its rotation, is within a predetermined distance of the cutting plane, and latching means adapted to latch said pusher plate in raised position at the 10 termination of a predetermined camming rotation.

17. In a slicing machine having a knife and means for actuating it, a carriage and means for guiding it past the cutting edge of the knife, a pusher plate mounted upon the carriage and means for guiding it for movement toward and away from the cutting plane, including a generally horizontal guide mounted upon the carriage, generally perpendicular to the cutting plane, a supporting connection intermediate guide and pusher plate including a member longitudinally and rotatably mounted upon the guide and means, responsive to rotation of said supporting connection and pusher plate about the guide and away from the carriage, for retracting the pusher plate from the cutting plane of the knife, when the pusher plate, at the beginning of its rotation, is within a predetermined distance of the cutting plane, and latching means adapted to latch said pusher plate in raised position at the termination of a predetermined camming rotation, including a member associated with the pusher plate and a plunger mounted upon the carriage, said plunger including an inclined surface adapted to be overridden by the member on the pusher plate and a locking surface adapted lockingly to engage said member after the member has overridden the first mentioned inclined surface, and yielding means adapted normally to hold said plunger in latching position.

WILLIAM J. CAMPBELL.
